UNITED STATES PATENT OFFICE.

JAMES FRANKLIN GURLEY AND WILSON EDGAR LEWIS, OF RALEIGH, NORTH CAROLINA.

SWITCH-STAND.

No. 906,130.

Specification of Letters Patent.

Patented Dec. 8, 1908.

Application filed January 8, 1908. Serial No. 409,836

To all whom it may concern:

Be it known that we, JAMES FRANKLIN GURLEY and WILSON EDGAR LEWIS, citizens of the United States, residing at Raleigh, 5 in the county of Wake and State of North Carolina, have invented a new and useful Switch-Stand, of which the following is a specification.

This invention relates generally to switch stands, and more particularly to that class 10 wherein there is a cage provided into which a switchman has to enter and lock himself in in the act of opening a switch to allow a train to pass upon the siding.

15 The object of the present invention is to improve and simplify the construction of such appliances and to render them more certain of action and less liable to become deranged in use.

20 With the above and other objects in view, as will appear as the nature of the invention is better understood, the same consists in the novel construction and combination of parts of a switch stand as will be hereinafter fully 25 described and claimed.

25 In the accompanying drawings forming a part of this specification and in which like characters of reference indicate corresponding parts,—Figure 1 is a view in side elevation, partly in section, of a switch stand constructed in accordance with the present invention. Fig. 2 is a horizontal sectional view taken on the line 2—2 of Fig. 1, and displaying the position of the parts when the 30 switch is closed. Fig. 3 is a similar view showing the position of the parts when the switch is open. Fig. 4 is a detail view of a portion of the operating mechanism.

35 Referring to the drawings, 1 designates a base of any suitable material which is supported adjacent to the tracks T. Upon this base is mounted a cage which is preferably circular in plan, and is composed of properly spaced iron bars that are secured at their lower ends in a band 2 secured to the base, and at their upper ends in a roof or cover 3. On one side of the cage is left a space 4 forming a doorway, the sides of which are formed by bars 5.

40 The doorway is adapted to be closed by a segmental door which consists of two castings 6 that are carried by a shaft 7 that extends through the base 1 at its lower end and above the roof 3 at its upper end, and carries 45 a semaphore or signal 8 of the usual or any 50 preferred construction. The two segments

of the door are connected by bars 9 which, when the parts are in the position shown in Fig. 3, will positively prevent egress through the doorway, this being the position that the 55 door will occupy so long as the switch is open.

The shaft 7 is stayed and braced by a standard 10 that is bolted to the base and carries a curved arm or support 11 upon which is bolted two stops 12 that are undercut, as shown in Fig. 1, to receive the switch lever 13 and each stop is provided with an orifice 14 to receive a pin 15 by which the switch lever may be locked in either of its adjusted 60 positions.

In order to render the door easy of operation, the lower segment carries a shaft 16 upon which is mounted a wheel 17 adapted to traverse a track 18 secured to the base. 65

70 The means for effecting the adjustment of the switch tracks S consists of a trammel 18^a that is secured to the lower end of the shaft and carries two slide blocks 19 that are bolted at 20 to a lever 21, the outer end of which 75 is secured at 22 to a bar 23 that connects the switch tongues S.

75 So long as the main line M is open, the door 6 will occupy the position shown in Fig. 2, but should it be desired to open the switch 80 for the purpose of allowing a train to enter a siding, the operator opens the door 4 grasps the lever 13 and throws it from the position shown in Fig. 2 to that shown in Fig. 3, whereupon the switch tongues will be actuated 85 through the trammel and lever and be shifted to the position shown in Fig. 3, thereby opening the switch. In this act the door is moved opposite the doorway 4 so that egress therefrom is impossible without first 90 throwing the switch lever to the position shown in Fig. 2, whereupon the doorway will be opened.

95 It will be noted by reference to Fig. 3 that the door is considerably greater in length 100 than the width of the doorway and this arrangement is adopted in order to render it impossible for the switchman to partly close the switch and then leave the cage as the length of the door will prevent this, as by the 105 time the door is fully open the switch will have been entirely closed.

110 The advantages arising from the use of the trammel with the switch tongue operating means is that it dispenses with the employment of gears, which are objectionable owing to the fact that they become rusted and thus

difficult to operate. By the employment of the trammel greater ease of action at all times will be secured as there will be no such close fitting between the slide blocks and the guides as will at any time cause the parts to become rust locked.

5 What is claimed is:—

1. In a switch stand, a cage having a doorway, a segmental door shiftable with relation 10 to the doorway, a shaft upon which the door is supported, a trammel carried by the shaft, switch tongues, and a connection between the trammel and the switch tongues.
2. In a switch stand, a cage provided with 15 a doorway, a shaft disposed within the cage and extending above and below the same, an arm secured to the base of the cage through which the shaft projects, a shifting lever secured to the shaft and arranged to traverse 20 the arm, a trammel carried by the shaft,

switch tongues, and a connection between the trammel and the switch tongues.

3. A switch stand comprising a cage provided with a doorway, a segmental cage-like door for opening and closing the doorway, a 25 roller for supporting the door out of contact with the base of the cage, a shaft to which the door is secured, a switch lever secured to the shaft, a trammel secured to the lower end of the shaft exteriorly of the cage, switch 30 tongues, and a connection between the trammel and switch tongues.

In testimony that we claim the foregoing as our own, we have hereto affixed our signatures in the presence of two witnesses.

JAMES FRANKLIN GURLEY.
WILSON EDGAR LEWIS.
